US0D1037604S

(12) **United States Design Patent** (10) **Patent No.:** **US D1,037,604 S**
(45) **Date of Patent:** **** Aug. 6, 2024**

(54) **FOOD BAR**

- (71) Applicant: **Generale Biscuit**, Clamart (FR)
- (72) Inventors: **Jerome Clement**, Saclay (FR); **Mohamed Diry**, Saclay (FR); **Cecile Doinel**, Saclay (FR); **Jean Pierre Flatin**, Saclay (FR); **Marine Jacquet**, Saclay (FR); **Lelia Notardonato**, Saclay (FR); **Edouard Page**, Saclay (FR)
- (73) Assignee: **Generale Biscuit**, Clamart (FR)
- (**) Term: **15 Years**
- (21) Appl. No.: **29/733,323**
- (22) Filed: **Apr. 30, 2020**

Related U.S. Application Data

- (62) Division of application No. 29/604,757, filed on May 19, 2017, now Pat. No. Des. 887,666.

CLAIM

The ornamental design for a food bar, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top and right side perspective view of a food bar;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof; and,

FIG. 7 is a front elevation view thereof.
